UNITED STATES PATENT OFFICE.

LORREN B. McCARGAR, OF ST. JOSEPH, MISSOURI.

GRINDING-MILL.

1,002,419.

Specification of Letters Patent. Patented Sept. 5, 1911.

Application filed April 24, 1911. Serial No. 623,097.

To all whom it may concern:

Be it known that I, LORREN B. McCARGAR, a citizen of the United States, residing at St. Joseph, in the county of Buchanan 5 and State of Missouri, have invented certain new and useful Improvements in Grinding-Mills; and I do declare the following to be a full, clear, and exact description of the invention, such as will enable others skilled in 10 the art to which it appertains to make and use the same.

This invention relates to grinding mills especially adapted for grinding ear corn with the shuck on and Kafir corn and Milo 15 maize in head, but which may also be used for grinding shelled corn or other grain without any change in the parts.

The object of the invention is to provide improved crushing and cutting devices by 20 which the shuck, grains and cob are broken sufficiently to be fed to the grinding burs.

Another object is to provide improved means for so crushing the corn that it may be fed rapidly.

25 With these and other objects in view, the invention consists of certain novel features of construction, combination and arrangement of parts as will be more fully described and particularly pointed out in the appended 30 claims.

In the accompanying drawings: Figure 1 represents a side elevation of a mill constructed in accordance with this invention; Fig. 2 is a vertical longitudinal section 35 thereof; Fig. 3 is a detail side elevation of the crushing and cutting mechanism; Fig. 4 is a detail vertical section of the cutting and crushing mechanism with parts broken out; Fig. 5 is a bottom plan view of the upper 40 movable cutter; Fig. 6 is a top plan view of the upper stationary cutter with the hopper shown in dotted lines; Fig. 7 is a bottom plan view of the lower movable cutter; Fig. 8 is a similar view of the lower stationary 45 cutter; Fig. 9 is a transverse section taken on the line 9—9 of Fig. 5; Fig. 10 is a similar view taken on the line 10—10 of Fig. 6; Fig. 11 is a similar view taken on the line 11—11 of Fig. 8.

50 In the embodiment illustrated a base plate 1 is shown on which the mill is mounted. This mill may be of any suitable or desired construction, the novel features residing in the peculiar crushing and grinding means 55 which will be hereinafter described.

This mill may be operated in any suitable

manner, it being here shown provided with a driving wheel 3 mounted on a horizontally disposed shaft 4 provided with a cog wheel 5, which engages a crown gear 6, secured to the lower end of a vertically disposed revolubly mounted shaft 7 to which a bearing sleeve 8 is fixed, said sleeve preferably having an angular socket in its lower end which fits over a correspondingly shaped portion 60 of the shaft 7. The cutting knives and grinding burs are mounted on said sleeve 8 and shaft 7 within a hopper 2.

The burs 8' may be of any suitable or desired construction and are mounted below 70 the cutting and crushing knives as shown in Fig. 4. The angular socket 9 of the bearing 8 is engaged with a correspondingly shaped portion 7' of the shaft 7 to provide for the turning of said bearing with said 75 shaft. This bearing 8 is provided on its outer face with alternately arranged round and angular portions as 10, 11, 12 and 13 to receive the rotary and stationary cutting knives to be described.

80 A horizontally disposed stationary knife 14 is arranged in the hopper 2 above the bur 8' and is constructed with an annular hub 15, the opening in which is circular and has a stepped face 16 for engaging the correspondingly shaped portion 13 at the lower 85 end of the tubular bearing 8 to permit the turning of the shaft 7 relatively to said knife 14. This hub 15 has five curved blades as 17 the free ends of which are notched or 90 recessed as shown at 18 to engage lugs as 2' on the inner face of the hopper 2 whereby said knife is held securely against turning. The sides of these blades 17 are hollowed out as shown in Figs. 8 and 11 to 95 form sharp cutting edges as 19 on the upper inner edges of said blades which form a shear for the revolving cutter 20 now to be described.

100 Arranged on the bearing 8 above the stationary knife 14 is the revoluble knife 20 having a plurality of radiating curved blades 21, three being here shown and each provided with a cutting edge at its top and bottom which act in conjunction with the 105 knives above and below it. The hub of this revoluble knife 20 has an angular opening 22 therein which fits over the angular portion 12 of the bearing 8 and thereby secures said knife to said bearing to provide for 110 its turning with the bearing on the rotation of the shaft 7.

A stationary knife 23 is arranged on the round portion 11 of the bearing 8 above the knife 20, the opening therein being round to provide for the turning of the bearing 5 without imparting motion to the knife. This knife is also provided with a plurality of radiating prongs or blades as 24 three being here shown and each provided with a cutting edge at its top and bottom as is shown 10 clearly in Fig. 10. The free ends of the arms or blades 24 are provided with notches or recesses as 25 which are adapted to engage lugs 2" secured to the inner face of the hopper 2 and which hold said knife securely 15 against turning.

A top knife 26 has an angular opening 27 therein which fits the angular portion 10 of the bearing 8 to provide for the revolution of said knife with said bearing. This knife 20 26 is provided with two oppositely disposed blades 29 to provide sufficient room for rapid feeding of the corn. These blades 29 are cut out on their lower faces as shown at 30 to provide for the passage through 25 the slots 31 therein of the bolts 32 which secure the ends of a force feed 33 to said knife and permit nuts 32' to be secured to the ends of the bolts without projecting into the path of the cutting edge of said 30 knife. These knives are constructed in cross section as shown in Fig. 9 with their upper faces curved as shown at 34 to provide the cutting edges 35 at the lower side thereof for co-operation with the cutting edges on the upper faces of the blades of 35 the knife 23.

The force feed 33 is here shown in the form of two curved blades secured to and depending from a sleeve 36 through which 40 the shaft 7 loosely passes, said feed being rotated by means of the top cutting knife 26 to which it is secured. A nut 37 or any other suitable means are arranged on the shaft 7 above the sleeve 36 to retain the 45 parts in operative position, jam nuts 38 being arranged on said shaft below said sleeve between it and the upper face of the knife 26.

A plurality of spirally disposed ribs as 50 39 are preferably arranged on the inner face of the hopper 2 which act as an auger in connection with the force feed to convey the corn to the knives.

In the operation of this improved mill 55 the hopper is supplied with corn on the ear and preferably in the shuck, which is first engaged by the blades of the force feed 33 and fed thereby to the upper knife 26 which cuts the ears into large pieces and 60 as these pieces approach the second knife 23 which has three blades they are ground a trifle finer and when they finally reach the lowermost knife 14, which is provided

with five blades the corn, cob and shuck are ground to the size of a grain of corn and 65 from thence it passes to the grinding burs 8' and may there be ground to any desired fineness according to the adjustment of the burs. The knives and burs are constructed of chilled steel and may be resharpened 70 when necessary.

From the foregoing description taken in connection with the accompanying drawings, the construction and operation of the invention will be readily understood without requiring a more extended explanation. 75

Various changes in the form, proportion and the minor details of construction may be resorted to without departing from the principle or sacrificing any of the advantages of the invention as defined in the appended claims.

I claim as my invention:

1. A grinding mill provided with alternately arranged stationary and revoluble 85 cutters, each having a plurality of radially extending cutting blades, the blades of said cutters gradually decreasing in number toward the upper end of the mill, whereby the material operated upon is gradually 90 ground finer in its passage through the mill.

2. A grinding mill having a stationary lower cutter provided with radially extending cutting blades, a revoluble cutter arranged above said stationary cutter, a stationary cutter arranged above said revoluble cutter, and a revoluble cutter arranged above said last mentioned stationary cutter, each of said cutters having radially extending blades, the blades of each cutter increasing in number from the top toward the bottom of the mill. 100

3. A grinding mill having a stationary lower cutter provided with a plurality of 105 radially extending curved cutting blades having sharpened upper edges, a revoluble cutter arranged above said stationary cutter and having sharpened edges on its upper and lower faces, a stationary cutter arranged 110 above said revoluble cutter and having a plurality of radially extending curved blades with sharpened edges at their upper and lower faces and a revoluble cutter arranged above said last mentioned stationary 115 cutter and having two oppositely extending blades provided with cutting edges on their lower faces, and a force feed secured to said upper cutter.

In testimony whereof I have hereunto 120 set my hand in presence of two subscribing witnesses.

LORREN B. McCARGAR.
